MATERIAL EXCAVATING, LOADING, TRANSPORTING AND PLACING MACHINE

Jack B. Halle, Detroit, Mich., assignor to Gar Wood Industries, Inc., a corporation of Michigan

Application August 10, 1938, Serial No. 224,131

10 Claims. (Cl. 37—126)

This invention relates to improvements in excavators, and particularly relates to the type in which a cutting blade is associated with a dirt hauling scoop, arranged within a frame structure, and which is utilized as a means for transporting the dirt graded or scraped from a surface.

Further, the present invention relates to the type of structure in which the scoop is pivotally connected directly to a main frame structure and is raised and lowered by an upward lifting and a lowering of the forward end of the frame, and in which the tilting of the scoop for dumping is by a controlled adjustment about its supporting connection with the main frame.

One of the primary objects of the present invention is to provide spring means at one end of the main frame which are compressed or loaded when the frame is lowered to digging position and which will quickly jump or raise the frame, in conjunction with a hydraulic cylinder, so that the cutting blade may be rapidly withdrawn from its bite in the earth. For the particular embodiment of the invention herein illustrated, the springs are located at the front end of the machine, but it is to be understood that they are not necessarily so placed, and may be positioned at the rear end, instead, and when so placed will function with substantially equal success. Another object accomplished by the springs is that the size of the hydraulic cylinder may be reduced from that heretofore required, with the result that the speed of piston travel is increased without increasing the output of the hydraulic pump which supplies the fluid to the cylinder, and without increasing the operating pressure of the hydraulic fluid.

A further object of the present invention is to provide a construction in which the gate-supporting arms are positioned inside of the side walls of the pivoted scoop but are not mounted on the scoop side wall, the pivotal mounting of these gate-supporting arms being on stationary side walls and at points above and very substantially rearwardly of the pivotal points about which the scoop moves; to provide front gate supporting arms of relatively long length and positioned so that when the gate is down it will be in load supporting position and at the same time the gate may be made to ride or float along on the top of soft material which is being loaded into the scoop; to provide a construction in which the width of the scoop most closely approaches the overall width of the entire machine; and to provide a machine of this class in-

which the material hauling scoop is of maximum capacity for the overall width of the machine.

An illustrative embodiment of this invention is shown in the accompanying drawings, in

5 which:

Fig. 1 is a view in side elevation with the machine in load transporting or hauling position in full lines and with the apparatus shown in dumping position in dotted lines.

10 Fig. 2 is an enlarged fragmentary sectional view taken on the line 2—2 of Fig. 1, looking in the direction indicated by the arrows.

Fig. 3 is an enlarged fragmentary sectional view taken along the line 3—3 of Fig. 1, looking 15 in the direction indicated by the arrows.

Fig. 4 is an enlarged fragmentary sectional view taken along the line 4—4 of Fig. 1, looking in the direction indicated by the arrows.

15 Fig. 5 is a top plan view of the machine shown 20 in Fig. 1.

Fig. 6 is an enlarged fragmentary sectional view taken along the line 6—6 of Fig. 1, looking in the direction indicated by the arrows.

Fig. 7 is a view in side elevation of the machine 25 in digging or excavating position.

Fig. 8 is a fragmentary view, in side elevation, with a portion thereof broken away, showing a modified form of gate lifting means which permits the gate to ride or float on the surface of 30 the ground being excavated.

Fig. 9 is an enlarged view partly in section and partly in elevation of one of the spring units in fully compressed position.

35 Fig. 10 is an enlarged fragmentary view, partly in section and partly in elevation, of the upper end of the unit shown in Fig. 9 but with the spring in extended position.

40 Fig. 11 is an enlarged fragmentary view, partly in section and partly in elevation, of the lower end of the unit shown in Fig. 9, but with the spring in extended position.

Machines of the character herein shown and 45 described are usually attached to tractors or the like which furnish the motive power for pulling the excavating machine. Such tractors are equipped with a hydraulic pump which is connected to the various hydraulic controls of the excavating machine for operating the same. Heretofore in the use of machines of this character the scoop is adjusted to digging position and pulled into the earth so as to fill the bowl or scoop with the material. As the digging blade of the scoop passes down into the earth and the bowl or scoop fills up with material the tractive 50 power required to pull the machine becomes

very great and when the pull of the machine upon the tractor is sufficient to practically stall the tractor, it becomes necessary to raise the cutting blade out of the earth to prevent stalling of the tractor. To do so means operation of the hydraulic pump and this throws a still greater horse power load upon the tractor, the result of which is that the tractor sometimes stalls.

In the present machine means are provided for storing up power, these means in the present form illustrated being a pair of relatively heavy helical compression springs. In the use of this machine, the hydraulic pump is actuated to compress the springs at the time when there is very little load on the scraper blade and therefore the tractor is well able to not only pull the machine, but at the same time operate the hydraulic pump for compressing the springs. Compression of the springs is also aided by the drawbar pull acting through a leverage arrangement and by the weight of the machine. As the scoop scraper blade digs into the earth and fills the scoop or keeps taking a heavier bite into the earth with the result that it approaches a stalling stage for the pulling tractor, it is then possible to raise the scoop out of the earth or jump it up quickly without throwing an appreciable greater horse power load upon the pulling tractor.

This is done by merely opening or cracking the valve in the hydraulic cylinder which holds the lifting springs compressed. The energy stored in these springs will thereupon tend to raise the machine upwardly and thereby withdraw the cutting blade and do so with very little help from the hydraulic pump which is attached to the lifting control. Furthermore, oftentimes in certain characters of earth all that is necessary to do is merely operate the hydraulic control until the springs are sufficiently compressed to bring the scraper blade into contact with the ground. Thereupon the drawbar pull aided by the angular slope of the scraper blade digging into the earth will tend to pull the machine down and thereby compress the lifting springs without material operation of the hydraulic pump to which the lifting control is attached. It will thus be seen that in some instances it is possible to store up energy in the lifting springs without throwing very much additional horse power load onto the tractor.

The net result of this arrangement is that a bigger or greater capacity excavating machine may be handled by a smaller tractor than heretofore and thus effect a very substantial economy in operation, as well as lessening the investment of capital in the original equipment.

Furthermore, by having a considerable amount of energy stored up in the lifting springs, it is readily possible to disengage or partially disengage the cutting blade from the earth just prior to the stalling of the tractor to which the machine is attached which in other instances without the lifting springs would be totally impossible. The quick action of the lifting springs as compared to the hydraulic cylinders usually employed for this purpose is extremely advantageous and results in a much more flexible machine.

Although in the present embodiment illustrated the lifting springs are mounted at the front end of the vehicle, it will be readily understood that this same action may be secured by having the lifting springs acting between the cutting blade and the rear supporting or ground wheels

of the excavating machine, the placing of the springs being merely a matter of preference.

In the construction shown in the drawings the improved excavating machine comprises a pair of spaced substantially parallel side frame members 15 and 16, one at each side of the machine which are connected adjacent the front and rear ends by cross frame members 17 and 18 respectively, thus forming a substantially square frame when viewed in plan as in Fig. 5 of the drawings. The rear ends of the side frame members 13 and 15 extend rearwardly beyond the cross frame member 18 and are provided with inwardly extending stub axles upon which ground wheels 19 and 20 are journaled.

The cross frame member 17 is tubular and extremely rigid in construction and at its medial point is provided with a forwardly and upwardly extending arm 21 welded or otherwise rigidly secured thereon. The member 17 is also provided with a pair of aligned, rigidly mounted forwardly extending, brackets 22 and 23, positioned one at each side of and closely adjacent to the base of the arm 21. The brackets 22 and 23 have pivoted thereto spaced parallel arms 24 and 25, respectively, which are integrally formed on a generally forwardly extending triangular shaped member 26 which converges toward the front and the forward end of which is rigidly secured as by welding to the top end of a generally upright strut 27 of semi-cylindrical cross-section. As shown most clearly in Fig. 4 of the drawings, the lower end of the strut 27 is rigidly mounted on a fitting 28, the lower end of which is provided with a cross-pin 29 upon which is pivoted a knuckle member 30. The knuckle 30 is also provided with a cross-pin 31 positioned at right angles to the pin 29 and which is mounted in a pair of upstanding spaced parallel ears 32, integrally formed on the top end of a vertically disposed king-pin 33. The king-pin 33 is pivotally mounted in the middle of a relatively short front axle 34, upon the opposite ends of which are journaled ground wheels 35 and 36. The front axle 34 is provided with a forwardly extending tongue or draw-bar 37.

Means are provided for controlling the pivotal movements of the strut 27 and member 26 integrally formed therewith relative to the arm 21 and side frames 15 and 16 and comprise a hydraulic ram generally designated 38 in Fig. 1 of the drawings. The hydraulic ram 38 comprises a cylinder 39 the lower end of which is pivotally mounted on a cross-pin 40 carried by the fitting 28 and the position of the parts is such that the cylinder 39 is partially surrounded by the strut 27 when the apparatus is in the position shown in Fig. 1. The cylinder 39 is provided with a piston having a piston rod 41 connected thereto and which extends through a suitable stuffing box in the upper or top end of the cylinder 39 and the outer end of which is pivotally mounted on a cross-pin 42. The pin 42 is carried by the forwardly extending arm 21 of the main frame, the details of the connection being shown most clearly in Fig. 3 of the drawings.

The opposite ends of the hydraulic ram cylinder 39 are provided with hydraulic conduits 43 which are connected to a source of fluid under pressure usually a hydraulic pump mounted on the tractor or motive power which moves the excavating machine, by flexible hose lines.

The fitting 28 at the lower end of the strut 27 is provided with a forwardly extending bracket 44 which carries a cross-pin 45, the opposite ends of which extend from the sides of the bracket

and upon which are mounted the lower ends of a pair of spring units generally designated 46. The spring units 46 are of identical construction, therefore a detailed description of one will suffice for both. As shown most clearly in Figs. 9, 10 and 11 of the drawings, each of the spring units 46 comprises a circular head or cap member 90 which is pivoted one on each end of a cross-pin 50 which is mounted transversely of and to the forwardly extending arm 21. The cap member 90 has a concentrically positioned axially extending rod or plunger 91 rigidly mounted thereon which slidably telescopes within a bushing 92 which is welded into the top end of a sleeve member 93. The sleeve 93 is integrally formed on one end of a collar 94, the other end of which is provided with a similar oppositely extending sleeve 95. The collar 94 has a radially extending annular flange 96 integrally formed thereon midway of its axial length which serves as a seat for one end of a helical compression spring 97. The other end of the spring 97 seats against the under side of the head member 90 and the spring is loosely guided by a sleeve 98 which is welded to the head 90, concentrically with respect to the rod 91. The outside diameter of the guide sleeve 98 is slightly less than the inside diameter of the spring convolutions. The sleeve 98 also serves to protect that part of the rod 91 which slides within the bushing 92 from much dirt and dust which otherwise would cause extensive wear and which would interfere with its sliding movement.

As shown most clearly in Figs. 9 and 11, a lower circular head member 99 has a concentrically positioned, axially extending tube 100 rigidly welded thereto which has sliding telescoping fit within the sleeve 95 and is of such length as to in slightly spaced relation to the bushing 92 when the unit is in fully telescoped position as shown in Fig. 9. The inside diameter of the tube 100 is slightly greater than the outside diameter of the rod 91 so that the rod can freely slide therethrough as is also shown in Fig. 9. The head member 99 also serves as a seat for the lower end of a helical compression spring 101, the upper end of which seats against the under side of the flange 96. The springs 97 and 101 are of such strength and construction that they will support a major part of the weight of the machine when fully loaded as will be hereinafter more fully explained.

The side frame members 15 and 16 have rigidly secured thereto vertically disposed, longitudinally extending, side wall plates 110 and 111, respectively, by angle bars 112 and 113, respectively, one flange of which is attached to the top surface of the side frame members 15 and 16 and the other flange of which is welded or otherwise rigidly secured to the side plate members 110 and 111. Between the side frame members 15 and 16 is pivotally mounted a carrying-scoop 114 on a pair of transversely disposed mountings 115 and 116 which are of identical construction and one of which is most clearly illustrated in Fig. 2 of the drawings.

The scoop 114 is provided with side walls, a rear end, and a bottom integrally formed, the front of the scoop being open, and the leading edge of the bottom being provided with an inclined cutting blade 117 after the usual manner of scoops of this character. Means are provided for rotating the scoop 114 about its pivotal connections 115 and 116 and comprise a pair of hydraulic rams 118 and 119, mounted one at each side of the scoop immediately above and longi-

tudinally of the side frames 15 and 16. When the scoop 114 is in normal position, as shown in full lines in Fig. 1 of the drawings, the rear end thereof is rigidly supported by a ledge or stop 150 which rests upon the rear cross member 18.

The construction, mounting, and arrangement of the hydraulic rams 118 and 119 are identical and, therefore, a detailed description of one will suffice for both. As shown clearly in Figs. 1 and 7, the rear or lower end of the cylinders of the hydraulic rams are pivotally mounted to the side frames by upstanding brackets 120 and 121, respectively, the upper ends of which carry pivot pins 122 and 123, respectively, upon which the respective cylinders are pivoted.

The cylinder of the hydraulic ram 118 is provided with a piston and a piston rod 124 connected thereto, one end of which protrudes from the other end of the ram cylinder through a suitable stuffing box. The outer end of the piston rod 124 is pivoted on a pin 125 which is mounted in a bracket 126 rigidly secured at the scoop 114 at a point above and to the rear of the point of pivotal mounting. Suitable hydraulic lead lines 127 and 128 are connected to and communicate with opposite ends of the ram 118 for conducting fluid under pressure to opposite ends of the ram cylinder as desired. The hydraulic lead lines 127 and 128 are of flexible material adjacent to their respective ends of the hydraulic rams in order to permit movement of the rams.

Means are provided for holding the dirt or other loose material in the scoop 114 and comprises a forwardly inclined gate 130 extending transversely across the front end of the bowl and provided at each end thereof with rigidly secured upwardly and rearwardly extending arms 131 and 132. The rear ends of the arms 131 and 132 are pivotally mounted on pins 133 and 134, respectively, which are mounted upon the inner sides of the side walls 110 and 111, respectively. Reinforcing plates 235 are welded or otherwise rigidly secured to the inner side walls 110 and 111 and extend between the pivots 115 and 116 which support the scoop 114 and the pivots 133 and 134, respectively, upon which the rear end of the gate supporting arms are secured.

The side walls 110 and 111 extend forwardly 50 of the front edge of the bowl member or scoop 114 so as to form side aprons between which the gate 130 is freely movable, the side aprons or forwardly extending portions of the side wall serving the purpose to prevent soft, loose material, such as sand, pushing out around the sides of the scoop and for aiding in directing and holding the sand so that it is gathered up and fed into the scoop.

By having the gate-supporting arms 131 and 132 secured to the stationary side wall as distinguished from having them pivoted to the side walls of the scoop, it is possible to have the gate-supporting arms of greater length without having the gate 130 interfere with the front cross frame member 17 during dumping movement of the scoop.

By having the gate-supporting arms relatively long and the gate inclined forwardly at considerable of an angle, it is possible, when loading soft material, to let the gate float or ride along on the surface of the material being scraped up and put into the scoop. This riding of the gate on the surface of the soft material aids materially in loading it into the scoop or scraper.

Means are provided for raising and lowering

the gate 130 and comprise a hydraulic ram 135 pivoted on a pin 136 to the forwardly and upwardly extending end 137 of the arm 21 and which has its piston 138 pivoted by a pin 139 to a bell crank lever 140 pivoted at 141 to an upstanding bracket 142 which is rigidly mounted on the arm 21 and front frame cross member 17. The outer end of the other arm of the bell crank 140 is pivoted at 143 to one end of a rigid link 144, the other end of which is pivoted to the medial part of the gate 130. With such a construction it is possible to not only lift the gate away from the front end of the scoop 114, but also "power down" or, in other words, close the gate by hydraulic power.

In the modification shown in Fig. 3 of the drawings, the bell crank lever 140 is connected to the gate 130 by a flexible connection such as a chain 145, by the use of which it is possible to raise the gate by hydraulic power, but the gate will float or ride along on the surface of the ground when loading soft material and will close by gravity when permitted by its controls. This is particularly useful when it is desired to have the gate float or ride along on the surface of loose material being loaded into the scoop 114.

Hydraulic lead lines 146 and 147 are provided which communicate with opposite ends of the hydraulic ram 135 and which are connected to a source of fluid under pressure as heretofore described with respect to the other hydraulic operating units of this machine.

In the operation of this machine, when it is desired to load earth or other material into the scoop 114, fluid under pressure is admitted into the hydraulic ram 38 at the upper end thereof which forces the piston therein downwardly, thus compressing the spring units 46. This movement causes the front wheel structure to move outwardly with respect to the frame of the machine as shown in Fig. 7 of the drawings, and thereby lower the side frames and scoop 114 to a digging position, that is, to a point where the cutting blade 117 engages with the ground. In digging some characters of earth, it is possible to start the digging by first rotating the scoop forwardly and thus cause the cutting blade 117 to engage the earth. Due to the angle of the cutting blade 117, the engagement with the earth tends to draw the whole machine downwardly, that is, causes the earth cutting edge to bite into the ground, and thus the forward movement of the machine during its scooping operation will tend to compress the spring units 46 with substantially very little or no aid from the hydraulic ram 38. Compression of the spring units 46 stores up a considerable amount of energy therein and the strength of these springs is such that when the scoop 114 becomes nearly filled or, if it is biting too deeply into the earth, the scoop may be quickly raised by merely opening the valve of the hydraulic ram 38, thereby permitting the spring units 46 to raise the machine to the position shown in Fig. 1 of the drawings.

Also by the use of the resilient spring connecting means 46 which tends to urge the forward end of the main frame upwardly, a smaller hydraulic cylinder may be used in the present structure than in the prior structures without increasing the working pressure. Furthermore, the smaller cylinder results in increased speed of movement without increased hydraulic pump output, which feature is particularly desirable in the case of this machine. When scraping up the dirt during loading of the scoop, particularly when

working in hard or stony ground, it is very helpful to be able to quickly jump the scraper blade upwardly, and the combination of a relatively small, fast moving cylinder of the hydraulic ram unit and the spring units 46 operates most satisfactorily. The extent to which the forward end of the frame is elevated may be controlled by controlling the application of the hydraulic medium to the hydraulic mechanism 38.

During the loading movement of the scoop, the gate 130 may be raised, depending upon the character of the ground being worked. In soft material, such as sand, it is sometimes desirable to let the gate ride along on the top surface of the material being gathered into the scoop. At other times it is desirable to raise the gate as shown in Fig. 7 of the drawings so as to leave a wide, free opening for the material to pass between the forwardly extending side aprons of the side walls 110 and 111 and be raised by the cutting edge of the blade 117 into the scoop 114.

During other loading conditions, it is desirable to raise the gate only slightly away from the forward edge of the scoop 114 and thus cause the material being loaded to pass through a relatively narrow slot into the scoop and, as the scoop fills up, this material will roll forwardly and part of it be supported upon and carried by the forwardly inclined gate 130.

In installations where the gate is connected to the bell crank 140 by the stiff link 144, it is possible to close the gate at any time by applying hydraulic medium under pressure to the ram 135 and thereby "power down" the gate to a closed position. Under other conditions, it is most desirable to have the gate close by gravity and in such instances the gate is provided with a flexible connection such as the chain 145, both forms of connecting means being provided with the machine when supplied to the customer.

When the scoop 114 has been fully loaded, the machine is raised to the position shown in full lines in Fig. 1 of the drawings and transported to the dumping ground. When it is desired to dump the scoop 114, hydraulic medium under pressure is applied to the hydraulic rams 118 and 119 at the rear ends thereof, thus forcing the pistons and piston rods outwardly as shown in dotted lines in Fig. 1, thereby rotating the scoop 114 forwardly about its pivots 115 and 116 and causing the material in the scoop to be dumped therefrom.

In instances where the material has a tendency to stick within the scoop, the hydraulic controls may be operated rapidly to power down the front end of the machine a few inches, thereby compressing the lifting springs, and then quickly release the hydraulic pressure. Thereupon the lifting springs will jump the machine up, and by quick repetition of this action, it is possible to vigorously shake the scoop and thereby dislodge any sticking material.

By having the gate 130 mounted upon relatively long arms, the pivot points of which are upon the stationary side walls of the machine, as distinguished from being pivoted upon the side walls of the movable scoop, the gate may be positioned closely adjacent to the front end of the machine, i. e. to the front cross member 17 and not interfere therewith upon rotation of the scoop, as would be the case if the gate-supporting arms were pivoted to the side walls of the scoop 114, and thereby movable when the scoop is rotated for dumping.

Another distinct advantage of having the gate

supporting arms mounted on stationary pivots, lies in the fact that the gate opening is set in relation to the surface of the ground and will not be disturbed or changed by rotative movement of the scoop on its pivots for adjusting the angle of the cutting blade.

Although but one specific embodiment of this invention has been herein shown and described, it will be understood that numerous details of the construction shown may be altered or omitted without departing from the spirit of this invention as defined by the following claims.

What is claimed is:

1. In a machine of the class described, a frame, a material load receiving bowl and scraper element mounted on said frame, ground wheels adjacent one end of said frame, resilient means interposed between said wheels and said frame for normally urging said scraper element and bowl upwardly, and hydraulic means for elevating and lowering said scraper element relative to said wheels.

2. In a machine of the class described, a frame, a scraper element mounted on said frame, wheels adjacent one end of said frame, resilient means interposed between said wheels and said frame for normally urging said frame upwardly, and hydraulic means for elevating and lowering said frame relative to said wheels.

3. A scoop scraper of the character described comprising a main frame, supporting ground wheels at the rear thereof, a rigid extension at the front thereof, link means pivotally attached to the extension of said main frame, front ground wheels pivotally secured to said link means, a material load receiving bowl and scraper element carried by the main frame, resilient means acting between said extension and said front ground wheels for normally urging said frame upwardly, and other means acting between the frame and front ground wheels for elevating and lowering the front end of said main frame.

4. A scoop scraper of the character described comprising a main frame, supporting ground wheels at the rear end thereof, a rigid extension at the front end of said frame, a material load receiving bowl and scraper element carried by the main frame rearwardly of said extension, a steerable wheel at the front end of said frame, resilient means acting between the extension and said steerable wheel for resiliently mounting said frame with respect to said steerable wheel and for normally urging said frame upwardly, adjustable means interconnecting the extension and said steerable wheel, a link means forming a triangle with said adjustable means, and said extension, all of which are pivoted to permit the shape of the triangle to be changed, and means for adjusting said adjustable means to alter the shape of the triangle and thereby vary the wheel base of said scraper.

5. In a scraper, relatively movable front and rear frames each being wheel supported, a scraper blade suspended from one of said frames and being movable toward and away from the ground by relative movement of said frames, a hydraulic

jack for relatively moving said frames, and spring means cooperating with said jack to assist the same in raising said blade and to cushion the lowering movement thereof.

6. In a scraper, a front frame having supporting wheels and extending rearwardly therefrom, a rear frame having supporting wheels and extending forwardly therefrom, a load carrying bowl suspended from one of said frames and having a scraper blade associated therewith, said frames being articulably interconnected at their respective rear and front portions and one of said frames having a rigid extension projecting beyond the axis of articulation and in proximity to the other frame, elevating means coacting with said extension and with said other frame to produce relative articulation thereof whereby said bowl and blade are raised and lowered, and a spring cooperating with said elevating means to assist the latter in raising said bowl and blade.

7. In a scraper, relatively movable front and rear frames each being wheel supported, a bowl suspended from one of said frames and having a scraper blade movable toward and away from the ground by relative movement of said frames, jack means for relatively moving said frames to raise and lower said bowl and blade, and spring means cooperating with said jack means to assist the same in elevating said bowl and to cushion the lowering movement thereof.

8. In a scraper, relatively movable front and rear frames mounted for transportation along the ground, a scraper blade suspended from one of said frames, a hydraulic jack interposed between said frames for relatively moving the same to raise said blade, and a series of compression springs cooperating with said jack to assist the same in elevating said blade and to cushion the lowering movement thereof.

9. In a scraper, pivotally interconnected front and rear frames mounted for transportation along the ground, a load receiving bowl suspended from one of said frames, a hydraulic jack having a cylinder pivotally attached to one of said frames and a plunger pivotally attached to the other frame, said cylinder and plunger being relatively movable to elevate said bowl, and compression springs disposed about said jack and coacting with said cylinder and plunger to assist the jack in raising said bowl.

10. In a scraper, a front frame having supporting wheels and extending rearwardly therefrom, a rear frame having supporting wheels and extending forwardly therefrom, a scraper blade suspended from one of said frames, said frames being articulably interconnected at their respective rear and front portions and one of said frames having a rigid extension projecting beyond the axis of articulation and in proximity to the other frame, elevating means coacting with said extension and with said other frame to produce relative articulation thereof whereby said blade is raised and lowered, and a spring cooperating with said elevating means to assist the latter in raising said blade.

JACK B. HAILE.
